United States Patent Office

Des. 180,754
Patented Aug. 6, 1957

180,754

RECIPROCATING SAW

Thomas M. Sweeney and James A. Kinsella, Joliet, Ill.

Application July 31, 1956, Serial No. 42,464

Term of patent 14 years

(Cl. D93—3)

Figure 1 is a perspective view of one side of a reciprocating saw embodying our new design;

Fig. 2 is a perspective view of the rear thereof; and
Fig. 3 is a front elevational view thereof.

The side opposite to that shown in Fig. 1, is identical.
We claim:

The ornamental design for a reciprocating saw, as
shown and described.
